EXPANSION AND CONTRACTION JOINT

Frank R. McFarland, Kansas City, Mo., assignor
to Sheffield Steel Corporation, Kansas City,
Mo., a corporation of Ohio

Application June 26, 1936, Serial No. 87,434

5 Claims. (Cl. 94—18)

This invention relates to expansion and contraction joints particularly for use in concrete pavements, and has for its principal objects to provide a joint of this character constructed to reinforce and maintain alignment of the pavement at opposite sides of a joint; and to provide the reinforcements with means for supporting a premolded filling strip in accordance with the grade.

10 Other important objects of the invention are to provide the reinforcement feature of the joint with means for positively retaining the dowels, or pavement aligning means, in parallelism and grade alignment during pouring of the concrete 15 so that all of the dowels are freely active in permitting expansion and contraction of the paving after it has set; to provide for distribution of live loads, acting on any one of the dowels across the width of the paving, to the other 20 dowels; and to provide a joint reinforcement that automatically conforms to the sub-grade incidental to its inherent flexibility in one direction but which has ample rigidity in lateral directions to maintain alignment of the filling strip 25 and load distributing bars as well as the dowels so that the relative positions thereof cannot become altered during pouring and setting up of the concrete.

It is also an important object of the invention 30 to provide an all welded reinforcement which which is of light weight and readily handled.

In accomplishing these and other objects of the invention, as hereinafter pointed out, I have provided improved details of structure, the preferred forms of which are illustrated in the accompanying drawings, wherein:

Fig. 1 is a perspective view of a portion of adjacent sections of paving equipped with an expansion joint embodying the features of the present invention, parts of the paving sections being broken away to better illustrate the construction.

Fig. 2 is a plan view with the adjacent ends of the paving sections broken away to illustrate the construction of the expansion and reinforcement features of the joint.

Fig. 3 is a cross-section through one side of the paving on the line 3—3 of Fig. 2.

Fig. 4 is an enlarged section taken transversely of the joint at one of the dowels.

Fig. 5 is a similar section through the joint taken at a point intermediate the dowels.

Fig. 6 is a perspective view similar to Fig. 1 but showing a modified form of construction.

Referring more in detail to the drawings:

55 1 designates a roadway or similar paved sur-

face formed of monolithic material, such as concrete, and which must be divided into sections 2 and 3 to provide expansion joints 4 whereby the respective sections may expand and contract in accordance with temperature and road conditions. The joints 4 are usually filled with a plastic material 5 to fill the expansion space and prevent entrance of dirt, water and other elements, that would interfere with expansive and contractive movement of the sections.

The adjacent paving sections 2 and 3 are ordinarily retained in alignment by means of dowel rods 6 imbedded in the concrete and extending transversely across the joint in parallel spaced relation. Alternate ends of adjacent dowels 15 usually are fixed in their respective paving sections, while the other ends are free to telescope in suitable sockets 7 sleeved thereon and imbedded in the sections as shown in Figs. 1 and 4. Unless the dowels 6 are supported in parallel spaced alignment and in a plane with the grade while the concrete is poured, they become disarranged and are moved out of parallelism, consequently the disarranged dowels will tend to prevent or at least resist expansive and contractive movement of the sections, and thereby result in cracking of the pavement. It is also necessary that the filling strips 5 be supported in transverse alignment and in a plane extending at right angles to the subgrade while the concrete is being poured.

As above pointed out, it is a principal object of the present invention to positively retain these parts against independent relative movement while the concrete is being poured, and to provide reinforcing means for distributing the load across the width of the paving adjacent the edges of the joint so that the live load acting above any one of the dowels is distributed proportionately to the other dowels, thereby obviating any tendency for the paving to crack because of unevenly distributed loads.

In accomplishing these results I provide an all welded unitary reinforcement and support for the dowel rods, as well as for the filling strip, so that they are retained in fixed relative position during pouring of the concrete, as now to be described.

8 designates a reinforcement and support embodying the present invention and which includes 50 a plurality of spaced primary chairs 9 located in corresponding relation to the desired spacing of the dowels, and each chair includes a bar or rod 10 bent to provide transverse footing portions 11 and upturned ends 12 and 13 to which are at- 55

tached load distributing and reinforcing bars 14 and 15 that extend across the paving on the respective sides of the expansion joint to connect the chairs. The bars are secured to the chairs by welding or the like, as indicated at 16, at the desired depth below the surface of the paving when the footing portions 11 rest upon the subgrade indicated at 17.

The ends 12 and 13 extend above the load distributing bars and have reversely bent terminals 18 and 19 of hook-like shape or loop. The terminals have ends 20 welded to the bars 14 and 15 at a point spaced from the welding points 16, as indicated at 21. The hook-like terminals thus cooperate with the bars to provide bearing openings 22 and 23 for slidably retaining the dowels 6, as clearly illustrated in Fig. 1.

Extending longitudinally of the bars 14 and 15 and welded to the under side of the footing portions 11 at points midway between the ends thereof, is a bar or rod 24 carrying a plurality of forks 25 located thereon midway between the chairs for supporting the premolded filling strip 5. The forks 25 include horizontal bar portions 26 welded to the rod 24 as indicated at 27, and have upstanding arms 28 and 29 cooperating with the bar portions to form seats 30 to support the strip 5 in parallel alignment with the load distributing bars.

30 The strip 5 is preferably premolded of plastic material having resilient characteristics so that it is compressible upon expansion of the paving sections and expandable when the sections contract to keep the joint filled. The strip 5 is of sufficient length to extend across the paving and has openings 31 therethrough that are positioned in alignment with the bearing openings of the chairs to accommodate the dowel rods. Cooperating with the chairs and preferably located in alignment with the forks are supplemental substantially L-shaped chairs 32 including rods having vertical leg portions 33 welded to the load distributing bars as at 34, and having lateral footing portions 35 extending in the direction of the forks for support on the subgrade. The dowels are so spaced that those adjacent the sides of the paving are inset from the sides thereof, however, the bars 14 and 15 and rod 24 extend across the entire width of the paving, making it desirable to support the ends of the bars by pairs of supplemental chairs 32 and to provide the ends of the rods with forks 25 to engagingly support the outer ends of the filling strip.

55 The form of the invention illustrated in Fig. 6 is substantially the same as the preferred construction, except that the supplementary chairs are omitted and rods 36 and 37 are welded adjacent the ends of the footing portions of the chairs as at 38 and 39 respectively.

60 The reinforcements above described, comprising the load distributing bars 14 and 15, the fork carrying bar 24, together with the primary and supplementary chairs, are welded together at the factory to form a solid unit which is shipped to the place of use. When received at the job they are distributed along the subgrade and placed in the position they are to assume in the finished paving. When placed on the subgrade the units are freely flexible in a perpendicular direction so that they readily take the curvature of the grade, however, the construction is such that the bars 14 and 15 and rod 24 will retain their parallel relationship. The reinforcements may thus be applied without the use of stakes or other means 75 for holding them in set position. The filling

strips are then applied so that the lower edges thereof engage within the seats of the forks. When thus engaged the strips are held perfectly straight and extend in parallelism with the load reinforcing bars. The dowels 6 are then applied by sliding them through the bearing portions of the chairs and through the openings 31 in the strip so that the ends thereof are supported upon and retained in fixed lateral relationship with the load distributing bars. The sockets 7 are then placed on alternate ends of the respective bars as shown in Figs. 1 and 2. The concrete or other monolithic material forming the paving is poured on the subgrade and levelled off as in conventional practice.

15 After the concrete has set, the paving sections are free to move to and from each other guided by the dowels which retain the surface of the paving in horizontal alignment.

Attention is directed to the fact that the chairs 20 are formed of relative light gauge material so that the footing portions thereof do not interfere with movement of the paving sections. Loads acting on one portion of the paving are transmitted across the width thereof by means of the 25 load distributing bars 14 and 15 so that the paving does not tend to crack. Likewise load forces acting on any one of the dowels are distributed to the other dowels through the bars 14 and 15 to spread and distribute the strains across the length 30 of the joint. Since the dowel rods are retained in parallelism during the pouring and setting of the concrete, it is obvious that they are free to 35 guidly support the sections during their expansive and contractive movement and thereby permit full expansion and contraction of the sections without imparting strains on the edges of the joint tending to crack or break the concrete.

From the foregoing, it is obvious that I have provided a reinforcement and support for expansion joints which is of light weight construction, and which accurately retains the dowel rods, as well as the filling strip, in their correct relation during pouring of the concrete. It is also obvious that the reinforcing is readily fabricated and incorporated in a paving construction in exact conformity with the subgrade, however, the structure has sufficient rigidity in a lateral direction to prevent displacement of the parts supported by it.

50 What I claim and desire to secure by Letters Patent is:

1. A unitary joint reinforcement including spaced load distributing bars, chairs rigidly connected with the load distributing bars, a fork supporting rod fixed to said chairs, forks fixed on said rod, a joint filling member having dowel apertures and arranged for edge support in said forks for retaining said member in rectilinear alignment, and dowels having sliding support relatively to the chairs and extending through said apertures of the joint filling member.

2. A unitary joint reinforcement including a plurality of spaced chairs, each comprising a bar formed to provide a horizontal footing portion having upturned ends terminating in loop portions, load distributing bars fixed to said upturned ends to connect said chairs, dowels slidably engaged in said loop portions, a fork supporting rod fixed to the horizontal footing portions of said chairs, and forks rigidly supported on said rod to cooperate with the dowels in supporting a joint filling strip in rectilinear alignment.

3. A unitary joint reinforcement including a plurality of spaced chairs, each comprising a bar

formed to provide a horizontal footing portion having upturned ends, load distributing bars attached to said upturned ends and connecting the chairs, a rod rigidly connecting the footing portions of said chairs, and seating means on said rod for aligningly supporting a joint filling member.

4. A unitary joint reinforcement including a plurality of spaced chairs, each comprising a bar formed to provide a horizontal footing portion having upturned ends, load distributing bars attached to said upturned ends and connecting the chairs, a rod rigidly connecting the footing por-

tions of said chairs, and forks fixed on said rod to aligningly support a joint filling member.

5. A unitary joint reinforcement including a plurality of spaced chairs, each comprising a bar formed to provide a horizontal footing portion having upturned ends, load distributing bars rigidly connected with said upturned ends to space said chairs, forks for aligningly seating a joint filling member, and means rigidly connecting the forks with the horizontal footing portions of said chairs.

FRANK R. McFARLAND.
